[57] CLAIM

The ornamental design for a portable entertainment center, as shown and described.

DESCRIPTION

FIG. 1 is an exploded front perspective view of a portable entertainment center showing my new design;
FIG. 2 is an exploded rear perspective view thereof;
FIG. 3 is a bottom perspective view of the lower portion of the center, the upper portion removed for convenience of illustration; and,
FIG. 4 is a front perspective view thereof.
The broken lines shown in the lower portion of the center in FIGS. 1, 3 and 4 represent scoring.
